CLAUDE G. BORDEAUX, OF SLINGERLANDS, NEW YORK

HEATING SYSTEM

Application filed June 12, 1930. Serial No. 460,632.

My invention relates to heating systems and particularly to systems for heating the interior of motor vehicles propelled by internal combustion engines.

The general objects of my invention are to provide a device of this character which may be readily attached to any internal combustion engine; which is simple and compact; which will positively operate with only periodic inspection and attention; in which there is no danger of asphyxiation or poisoning from the gases of combustion; in which the heat radiating element or elements may be comparatively small because of the high temperature at which the system operates; and which will begin to operate at high temperatures substantially with the starting of the engine. More specifically, my invention includes certain novel elements and arrangements thereof whereby a comparatively small volume of water is rapidly heated and expanded in a primary heater to cause an intermittent overflow therefrom to a vaporizer or superheater which, in turn, supplies steam to the heating system, together with means for automatically replenishing the supply of water in the primary heater.

With these objects in view my invention includes the novel elements and the combinations and arrangements thereof described below and illustrated in the accompanying drawings, in which—

Fig. 1 is a diagrammatic side elevation of my system showing a fragmentary portion of a motor vehicle;

Fig. 2 is an enlarged cross sectional view of the primary heating element of my system;

Fig. 3 is an enlarged cross sectional view of a vaporizing or superheating element;

Fig. 4 is an enlarged cross section of a needle valve arrangement for regulating the supply of water to the system;

Fig. 5 is a cross section of Fig. 4 in the plane 5—5;

Fig. 6 is a plan view of a valve element;

Fig. 7 is an elevation view, partially in section, of a radiator with an air purging device;

Fig. 8 shows a detail of the air purging device;

Fig. 9 is a side view of the device shown in Fig. 8, and

Fig. 10 is a fragmentary sectional elevation illustrating the radiator located beneath the seat of a vehicle.

Referring to the drawings, 1 is an internal combustion engine provided with the usual exhaust pipe, 2. Appropriately mounted near the exhaust pipe is a vaporizing and superheating element, 3. This element comprises an outer casing, 4, and an inner casing, 5, spaced from the outer casing to form between them a hot gas chamber, 6, communicating directly with the exhaust pipe, 2, through pipes, 7. The casing, 5, forms a chamber within which water, supplied from a source hereinafter described, is vaporized and superheated, and this casing may be provided on its exterior surface with flanges, 8, adapted to absorb heat from the gases of combustion and transmit it to the water or vapor in the superheating chamber.

9 represents generally a primary heating element within which the water or other volatile liquid used in the heating system is pre-heated and expanded to effect delivery to the superheater. Heat is supplied to this element by the flow of exhaust gases from the chamber, 6, through pipe, 10, a chamber, 11 (see Fig. 2) and the pipe, 12, back to the main exhaust pipe, 2.

The element, 9, comprises a casing, 13, preferably cylindrical, which is threaded into a flanged element, 14, forming a closure therefor at the bottom. Externally threaded on the element, 14, is a chamber forming means, 15, provided with openings, 16 and 17, adapted to permit the flow of the exhaust gases through said chamber. The element, 14, is provided with a centrally disposed, internally threaded boss, 18, and a small tubular element, 19, provided with heat absorbing flanges, 20, is threaded into the boss, 18, and depends downwardly into the chamber, 11. A short pipe, 21, is threaded into the upper portion of the boss, 18, and serves to support a valve element, represented generally by the numeral 22, which is designed to regulate

the supply of water delivered to the tubular element, 19.

This valve comprises an annular member, 23, threaded on the pipe, 21, and which is provided with a number of vertically extending passages, 24, arranged circumferentially about the central opening, 25, therein. These openings are normally sealed by a washer, 26, which simply lies on top of the element, 23. Threaded on the member, 23, is a cover, 27, 10 the top of which is spaced somewhat above the washer, 26, so that clearance is provided for the washer to be raised to the position, 26', for example. Connected to the cover, 27, is a small pipe, 28, which leads upwardly and 15 out of the casing, 13; the joint between the pipe, 28, and casing, 13, being sealed. This pipe, 28, extends upwardly and opens into the superheating chamber, as best shown in Fig. 3.

20 A water reservoir, 29, provided with a vented filler cap, 30, is provided, as shown in Fig. 1, having its bottom about on the level with the bottom of the chamber, 13, and its top at about the level of the top of chamber, 13. The water reservoir communicates with the lower part of the casing, 13, by means of pipe, 31, and, between the water reservoir and casing, 13, there is interposed in the pipe line, 31, a needle valve, 32, shown in detailed cross section in Figs. 4 and 5. This valve element is provided with a needle, 33, adapted to seat in the openings, 34, and the needle, 33, is centrally secured to a rather loosely fitted piston, 35, adapted to move in cylinder, 36; the piston, 35, being provided with guiding elements, 37, coacting with slots in the cylinder walls to maintain the piston substantially normal to the cylinder axis.

40 In operation, water is introduced into the reservoir, 29, and the system is filled by filling the reservoir, 29, to capacity. Bearing in mind that the piston, 35, fits cylinder, 36, rather loosely, the water pressure opens the 45 needle valve and the water seeps past the piston during the filling operation and fills the chamber, 13, to the top. The water pressure in the chamber, 13, acting upwardly through the passages, 24, against washer, 26, raises 50 the washer and permits water to flow downwardly into the tubular element, 19.

When the engine is started, the hot gases of combustion will exhaust through the chamber, 6, and downwardly through pipe, 10, 55 through chamber, 11, about the tubular element, 19, and thus outwardly through the pipe, 12, into the main exhaust pipe, 2. To shut off the heating system, the passage of the gas from chamber, 6, to chamber, 11, is 60 prevented by a suitable butterfly valve, 38, with an operating rod, 39, provided as shown in Figs. 1 and 3. When this valve is opened the small quantity of water in the tubular element, 19, is heated, and by expansion is 65 forced upwardly through the pipes 19 and 28,

into the superheating chamber where it is entirely vaporized and superheated and passes upwardly through the pipe, 40, to the upper part of the radiator, 41, which in the embodiment illustrated is located in a space 41a separated from the remaining portion of the heating system. Here, the vapor expends its heat and is condensed, the condensation flowing downwardly through the radiator and into pipe, 42, back to the casing, 13, through the opening 43. In addition to its function of placing the heating system in or out of operation, the valve, 38, is used to control the feeding of water to the generator and thus indirectly regulate the heating of the vehicle. 80

It will be obvious that as pressure is developed in the system comprising the tubular element, 19, the pipe, 28, and the superheating chamber, the pressure will tend to hold the washer, 26, closely over the passages, 24, 85 so that no more water can enter the tubular element. In order to balance the pressure on both sides of the valve washer, 26, the superheating chamber is connected to the upper part of the chamber, 13, by means of a pipe, 44. Also any excess pressure upon the lower side of washer, 26, due, for example, to returning condensate, will effect an opening of the valve and a flow of water to element, 19. 90

Provided there is no loss of water in the system, the vaporization of the water, the superheating and the condensing will continue indefinitely as long as heat is applied about tubular element, 19. To put the system out of operation it is only necessary to close the butterfly valve, 38, thus cutting off all heat about the tubular element, 19, and preventing further expansion or vaporization of water. Furthermore, as pressure develops in the system it will be apparent that the needle valve, 32, will be maintained in closed position because the pressure in the system will naturally exceed the atmospheric pressure on the water in reservoir, 29. When, however, the heating system is shut off by 100 closing valve, 38, and any water has been lost in the system, a partial vacuum will be created therein which will permit opening of the needle valve by atmospheric pressure, and replenishing of the water in the heating 105 system. 110

In Fig. 7 I have illustrated a radiator equipped with an automatic air-purging valve which may be used in my system. 45 represents the radiator shell which in this case is 115 preferably cylindrical and threaded at one end to receive the cap, 46, enclosing the purging valve. Threaded into the cap, 46, is a diaphragm, 47, having openings, 48, therein and centrally supporting an expansible element, 49, such as a sylphon bellows filled with ether. This bellows carries a needle, 50, adapted to seat in an opening, 51, in the end of cap, 46, when the bellows is expanded. Vapor is introduced into the radiator through 120 125 130

pipe, 40, and condensate flows off through pipe, 42.

In operation, this radiator may be substituted for the radiator 41. The expandible element is adjusted so that, at ordinary temperatures, the needle, 50, is withdrawn from its seat and air may pass through the valve opening in the end of cap 46. When the steam from the superheater enters the radiator it forces the air out through the cap opening until the bellows is expanded sufficiently to close the vent.

It will be apparent from the foregoing that my system will begin to heat almost immediately upon the starting of the engine because of the very small amount of water in the primary heater. This latter device operates very much like a percolating coffee pot in that the water is forced upwardly through 20 the pipe, 28, into the superheater in a manner quite similar to the water movement in such a device.

If the system is entirely sealed, of course, theoretically at least, no water is lost and 25 no reserve reservoir, such as 29, is necessary. However, the provision of this element permits the system to operate without attention for a much longer time than a system having no reserve supply and I therefore prefer to include it in my system.

While I have described my invention in its preferred embodiment it is to be understood that the words which I have used are words of description rather than of limitation and that changes within the purview of the appended claims may be made without departing from the true scope and spirit 35 of my invention in its broader aspects.

What I claim is:—

40 1. In a heating system, a source of hot gases, a radiator, a steam generator, a conduit connecting said generator to said radiator, a primary heater and generator feeding device connected to said generator and adapted to contain a small quantity of liquid, means for heating said primary heater by said hot gases and thereby expanding the fluid therein and forcing the same into said generator in small quantities, and means for 45 returning the condensate from said radiator to said primary heater.

2. In a heating system, a source of hot gases, a radiator, a steam generator, a conduit connecting said generator to said radiator, a primary heater and generator feeding device connected to said generator and adapted to contain a small quantity of liquid, means for heating said generator by said hot gases, means for heating said primary heater and thereby expanding the fluid therein and forcing the same into said generator in small quantities, and means for returning the condensate from said radiator to said primary heater.

55 3. In a heating system, a source of hot

gases, a radiator, a steam generator, a conduit connecting said generator to said radiator, a primary heater and generator feeding device connected to said generator and adapted to contain a small quantity of liquid, means for heating said generator and said primary heater by said hot gases and thereby expanding the fluid in said primary heater and forcing the same into said generator in small quantities, and means for returning the condensate from said radiator to said primary heater.

4. In a heating system, a source of hot gases, a radiator, a steam generator, a conduit connecting said generator to said radiator, a primary heater and generator feeding device connected to said generator and adapted to contain a small quantity of liquid, means for heating said primary heater by said hot gases and thereby expanding the fluid therein and forcing the same into said generator in small quantities, means for returning the condensate from said radiator to said primary heater, a liquid supply reservoir and means for feeding liquid from said supply reservoir into said heating system.

5. In a heating system, an internal combustion engine, a radiator, a steam generator, a conduit connecting said generator to said radiator, a primary heater and generator feeding device connected to said generator and adapted to contain a small quantity of liquid, means for heating said generator and said primary heater by the exhaust gases from said internal combustion engine and thereby expanding the fluid in said primary heater and forcing the same into said generator in small quantities, and means for returning the condensate from said radiator to said primary heater.

6. In a heating system, an internal combustion engine, a radiator, a steam generator, a conduit connecting said generator to said radiator, a primary heater and generator feeding device connected to said generator and adapted to contain a small quantity of liquid, means for heating said generator and said primary heater by the exhaust gases from said internal combustion engine and thereby expanding the fluid in said primary heater and forcing the same into said generator in small quantities, means for returning the condensate from said radiator to said primary heater, and means for controlling the amount of exhaust gases flowing over said primary heater.

7. In a heating system, an internal combustion engine, a radiator, a steam generator, a conduit connecting said generator to said radiator, a primary heater and generator feeding device connected to said generator and adapted to contain a small quantity of liquid, a reservoir communicating with said primary heater for supplying liquid thereto, automatic means for controlling the supply

- of liquid from said reservoir to said primary heater, means for heating said generator and said primary heater by said hot gases, means for returning the condensate from said radiator to said primary heater, and means for controlling the amount of heat applied to said primary heater.
8. In a heating system, an internal combustion engine, a radiator, a steam generator, a conduit connecting said generator and said radiator, a primary heater and generator feeding device connected to said generator and adapted to contain a small quantity of liquid, a liquid supply means for said primary heater, means comprising a valve having a normally closed element for controlling the flow of liquid from said liquid supply means to said primary heater, means for heating said primary heater by the exhaust gases from said internal combustion engine and thereby forcing liquid therefrom into said generator by the expansion of fluid in said primary heater and in quantities sufficiently small to be entirely vaporized in said generator, and means for returning the condensate from said radiator to said primary heater.
9. In combination, a vehicle, an internal combustion engine mounted therein, a heating system comprising a radiator located in a space separated from the remaining portions of the system, a conduit connecting said generator to said radiator, a primary heater and generator feeding device adapted to contain a small quantity of liquid, means for heating said generator and said primary heater by the exhaust gases from said internal combustion engine and thereby expanding the fluid in said primary heater and forcing the same into said generator in small quantities, and means for returning the condensate from said radiator to said primary heater.
